Primary Examiner — Philip S Hyder*Assistant Examiner* — Roselynne Cody(74) *Attorney, Agent, or Firm* — Greenberg Traurig, LLP(57) **CLAIM**

The ornamental design for a hammer head, as shown and described.

DESCRIPTION

FIG. 1 is a perspective view of my design;

FIG. 2 is a top view thereof;

FIG. 3 is a bottom view thereof;

FIG. 4 is a rear view thereof;

FIG. 5 is a front view thereof; and,

FIG. 6 is a right side view thereof, the left side view being a mirror image thereof.

The dashed lines in FIGS. 1-6 represent a generic handle that forms no part of the claimed design.

1 Claim, 2 Drawing Sheets(56)
